UNITED STATES PATENT OFFICE.

PHILIP HEFFLER, OF PITTSBURGH, PENNSYLVANIA, ASSIGNEE OF ONE-HALF TO
HARRY C. SIMMONS, OF CRAFTON, PENNSYLVANIA.

OIL STILL.

Application filed January 28, 1922. Serial No. 532,352.

To all whom it may concern:

Be it known that I, PHILIP HEFFLER, a citizen of the United States, residing at Pittsburgh, in the county of Allegheny and 5 State of Pennsylvania, have invented new and useful Improvements in Oil Stills, of which the following is a specification.

This invention relates to oil stills, and more particularly to an oil still provided 10 with means for effecting a uniform heating of the still throughout its full length.

One of the main objects of the invention is to provide a still of simple construction and operation which may be erected at comparatively small cost and in which checkers are employed, these checkers acting to give a uniform heat for the length of the tank or container of the still and also serving to effect saving in fuel. A further object is to 20 provide simple and efficient means for controlling the operation of the checkers. Further objects will appear from the detailed description.

In the drawings:—

25 Figure 1 is a central sectional view through a still constructed in accordance with my invention, the retort or container being shown in elevation;

Figure 2 is a horizontal sectional view 30 through the still looking down;

Figure 3 is a section taken substantially on line 3—3 of Fig. 1;

Figure 4 is a section taken substantially on line 4—4 of Fig. 1.

35 A suitable container or tank 1 is supported in the upper portion of a casing 2 of refractory material which may be constructed in any suitable or preferred manner, this tank being adapted to receive oil which it is 40 desired to distill. The tank is preferably provided with a covering 3 of heat insulating material and is of a known type.

End wall 4 of casing 2 is provided with an 45 opening 5 to admit the products of combustion from a furnace which, in practice, is built closely adjacent to wall 4, any suitable or preferred type of furnace being employed. A roof 6 is supported by wall 4 and a bridge 7 disposed in spaced relation to the wall, the 50 upper face of this roof being flush with the lower wall of opening 5. A checker 8 is positioned between bridge 7 and a bridge 9 extending across casing 1. This checker is formed in a known manner of a plurality

of bricks of refractory material which are 55 stacked in layers, the bricks of alternate layers being oppositely disposed. Checker 8 is supported upon tiles 10 which are supported upon walls or pillars 11 which extend longitudinally of casing 2 from bridge 7 60 to bridge 9. A second checker 12 is constructed between bridge 9 and the other end wall 4^a of casing 2, this second checker being supported upon tiles 13 which are supported by pillars or walls 14 supported by a 65 tile partition member 15 which is supported upon the forward portions 11^a of pillars or walls 11.

A conduit 16 extends from end wall 4^a of casing 2 and may be connected to a stack 70 for discharging the products of combustion flowing from the still. This conduit is divided by an arch 17, at its inner portion, into an upper passage 18 communicating with the space beneath checker 12, and a 75 lower passage 19 communicating, by means of the spaces between supporting walls or pillars 11^a, with the space beneath checker 8, it being understood that the partition member 15 fits snugly against the inner end 80 of arch 17 so as to prevent communication between passage 19 and the space beneath checker 12. A damper shaft 20 extends through arch 17 and across the passages 18 and 19. Two dampers 21 and 22 positioned 85 in passages 18 and 19, respectively, are secured on shaft 20, these dampers being disposed at right angles to each other. When the shaft is in the position illustrated in Figure 1, passage 19 is closed by damper 22 90 and passage 18 is open and in direct communication with conduit 16. Any suitable or preferred means for turning the damper shaft may be employed, such as an arm 23 secured on the upper end of the shaft and connected by pin and slot connections 24 to one end of a link 25 the other end of which is connected by pin and slot connections 26 to an angle lever 27 pivoted at 28, the other arm of this lever being connected by pin 100 and slot connections 29 to a pull rod 30 by means of which the lever may be rocked for turning the shaft into either of its operative positions. To protect the arm 23 and associated parts, a suitable housing or covering 31 may be provided. An air flue 32 communicates with the space beneath the checker 12, a similar flue 33 communicating with

95

100

105

105

the space beneath the checker 8. Each of these flues is provided with a damper 34 of any suitable or preferred type.

In practice, when the still is first placed in operation, dampers 21 and 22 are in the positions illustrated in Figure 1. The products of combustion from the furnace flowing through opening 5 into casing 2 travel the full length of the casing and are drawn downwardly through checker 12, flowing through passage 18 into conduit 16. This serves to heat tank or container 1 for the full length thereof. After this operation has been continued for a period of approximately two hours, the bricks of checker 12 have been heated to incandescence and shaft 20 is then turned so as to reverse the relative positions of the dampers, passage 18 being closed by damper 21 and passage 19 being placed in direct communication with conduit 16. At this time damper 34 of the flue 32, which is initially closed, is opened. This causes the products of combustion from the furnace to flow downwardly through checker 8 into the spaces between pillars or walls 11 and 11^a and through passage 19 to conduit 16. This downward flow of the products of combustion through checker 8 causes air to be drawn through air flue 32 and upwardly through the checker 12, this air being heated to a very high temperature and thus heating the forward portion of tank or container 1 so as to obtain a uniform temperature throughout the length of the container. To facilitate flow of the products of combustion through checker 8 the bottom wall of the casing between pillars or walls 11 is inclined downwardly toward end wall 4^a, at 8^a, a suitable opening being left to admit air from flue 33. When the checker 8 has been heated to the desired temperature by the products of combustion flowing through this checker, shaft 20 is turned so as to return the dampers 21 and 22 to their initial positions and damper 34 of air flue 33 is opened, the damper of air flue 32 being closed. This causes the products of combustion to flow over checker 8 and downwardly through checker 12, air being drawn through flue 33 and upwardly through checker 8, this heated air supplementing the heat of the products of combustion for producing an intense heat beneath the tank or container 1. By reversing the operation in the manner described the checkers 8 and 12 serve to absorb heat which would otherwise be wasted and also obtain a more uniform heating of the tank or container 1.

As will be understood, it may be found desirable in practice to resort to changes in details of construction and arrangement of parts of the invention without departing from the field and scope of the same, and I intend to include all such variations, as fall within the scope of the appended claims, in

this application in which a preferred form only of my invention is disclosed.

What I claim is:

1. In an oil still, a casing provided with an opening for entrance of the products of combustion from a furnace, a container supported in the casing and above said opening, checkers within the casing beneath the container, and means for causing the products of combustion to flow through either of the checkers, selectively, and for causing air to flow upwardly through the other checker.

2. In an oil still, a casing provided with an opening for entrance of the products of combustion from a furnace, a container supported in the casing and above said opening, checkers within the casing beneath the container, means for admitting air beneath either of the checkers optionally, and means for causing the products of combustion to flow through either of the checkers, optionally.

3. In an oil still, a casing provided with an opening for entrance of the products of combustion from a furnace, a container supported in the casing and above said opening, checkers within the casing beneath the container, separate passages communicating with the spaces beneath the respective checkers, air inlet flues communicating with the spaces beneath the respective passages, and means for closing either of said passages, optionally, and opening the other passage.

4. In an oil still, a casing provided with an opening for entrance of the products of combustion from a furnace, a container supported in the casing and above said opening, checkers within the casing beneath the container, separate passages communicating with the spaces beneath the respective checkers, air inlet flues communicating with the spaces beneath the respective checkers, a damper shaft rotatably mounted through said passages, and dampers secured on said shaft and disposed at right angles to each other, said dampers being positioned in the respective passages and adapted to close the same when in operative position.

5. In an oil still, a casing provided with an opening for entrance of the products of combustion from a furnace, a container supported in the casing and above said opening, checkers within the casing beneath the container, separate passages communicating with the spaces beneath the respective checkers, means for admitting air to the spaces beneath either of the checkers optionally, a damper shaft rotatably mounted through said passages, and dampers secured on said shaft and disposed at right angles to each other, said dampers being positioned in the respective passages and adapted to close the same when in operative position.

In testimony whereof I affix my signature,
PHILIP HEFFLER.
